Primary Examiner — Karen E Kearney*Assistant Examiner* — Debra Callahan(74) Attorney, Agent, or Firm — McAndrews Held & Malloy, Ltd.(57) CLAIM

The ornamental design for a display screen or portion thereof with icon, as shown and described.

DESCRIPTION

FIG. 1 is a front view of a display screen or portion thereof with icon showing our new design; and, FIG. 2 is an additional front view thereof showing additional, unclaimed subject matter.

The dash-dot broken lines in the figures represent an unclaimed boundary line and form no part of the claimed design.

The outermost broken lines in FIG. 2 showing a display screen or portion thereof are included for the purpose of illustrating portions of the article and form no part of the claimed design.
